UNITED STATES PATENT OFFICE.

WALTER T. CHARLES, OF CHICAGO, ILLINOIS.

FIRE-EXTINGUISHER.

1,228,746.

Specification of Letters Patent. Patented June 5, 1917.

Application filed June 17, 1916. Serial No. 104,190.

To all whom it may concern:

Be it known that I, WALTER T. CHARLES, a citizen of the United States of America, and a resident of Chicago, county of Cook, 5 and State of Illinois, have invented certain new and useful Improvements in Fire-Extinguishers, of which the following is a specification.

The main objects of this invention are to 10 provide an improved form of liquid squirting apparatus particularly adapted for use as a fire extinguisher; to provide an improved fire extinguisher apparatus which will discharge substantially all of its 15 contents regardless of the position in which it is held; and to provide an improved fire extinguisher apparatus wherefrom the fire extinguishing liquid is discharged by means of air pressure.

20 An illustrative embodiment of this invention in the form of a fire extinguisher is shown in the accompanying drawings, in which:

Figure 1 is a longitudinal section.

25 Fig. 2 is a detail of the piston in one of its positions.

Fig. 3 is an enlarged detail showing the valve head coacting with the valve seat for preventing accidental leakage at the nozzle.

30 Fig. 4 is a top plan detail of the inwardly facing flanges which are engaged by shoulders on the piston rod for locking the latter in its innermost position.

Fig. 5 is an enlarged sectional detail of 35 the piston rod end piece.

In the construction shown in the drawings, an elongated tubular casing 1 is provided with caps 2 and 3 brazed on the opposite ends thereof forming a receptacle adapted to contain a liquid. The upper cap 2 of the casing is provided with a filler opening having a plug 4 threaded therein.

45 A pump cylinder 5 is rigidly mounted in the center of the casing 1, and is supported at its opposite ends on the end caps 2 and 3 of the casing. The upper end of the pump cylinder extends through the cap 2 and is provided with nuts 6 and 7 that serve as local reinforcement for the cap and for making an air tight connection. A piston 8 is slidably mounted in the pump casing 5, and has a limited range of movement on the lower end of a relatively large hollow piston rod 9, the upper end of which carries a handle 10.

A stuffing box 11 is threaded into the end of the pump cylinder 5 and a gland 11.1 is threaded into the stuffing box so as to surround and bear against the piston rod 9. A downwardly flaring cap 12 is secured to the 60 piston rod 9 for covering over the stuffing box and nuts.

In the present embodiment the piston rod 9 is tubular and the lower end is threaded to receive an end piece 13 on which the piston 65 8 is slidably mounted. The end piece 13 is provided with upper and lower shoulders 14 and 15 respectively for limiting the sliding movement of the piston, and is also provided with an elongated slot 16, the lower 70 end of which is spaced slightly above the shoulder 15 and the upper end of which extends above and past the shoulder 14.

Air may be admitted into the pump cylinder below the piston 8 by means of an 75 air inlet 17 located in the upper end of the hollow piston rod 9, the piston rod end piece 13 having a centrally located pipe 17.1 soldered therein for conducting the air in the piston rod 9 past the slot 16. A check 80 valve 18 is located in the lower end of the end piece 13 for preventing the escape of air which has been drawn into the pump cylinder. The upper end of the pump cylinder is provided with an air outlet valve 85 19, which communicates with the interior of casing 1, so that air pumped in through the inlet 17 may be discharged into the casing for displacing the fire extinguishing liquid therein.

The lower end 3 of the device is depressed 90 inward and has a discharge nozzle 20 passing therethrough and threaded into a tubular fitting 23 which is threaded into the lower end of the pump cylinder 5. The nozzle 95 20 has a centrally located aperture 21, the inner end of which is flared outward, and the surrounding rim of which is shaped to form a valve seat 22. The lower end of the pump cylinder is closed by the fitting 100 23, which is provided with a centrally located aperture through which extends a valve stem 24 having a valve head 25 at its lower end adapted to coact with the valve seat 22. Surrounding the stem 24 above the fitting 23 is a coiled compression spring 26, which bears against the fitting and a top 105 part 27 on the valve stem, said compression spring being adapted to urge the valve head 25 away from the valve seat 22.

The top 27 of the valve stem is located directly under the end 28 of the piece 13, and when the piston rod is thrust inward to its full limit the valve stem 24 is forced downward, thereby seating the valve head 25. Means are provided for locking the piston rod in its innermost position, and comprise a pair of inclined shoulders 29 formed on the lower end of the end piece 13 in position to wedgingly engage under inwardly facing flanges 30, which are rigidly mounted on the interior of the pump cylinder 5.

A valve cylinder 31 is rigidly mounted on the pump cylinder 5 medially of its ends, and a pair of flexible discharge pipes 32 and 33 are provided each having one end mounted on and communicating with opposite ends respectively of said valve cylinder. The other ends of said pipes are free and are surrounded by suitable weights 34 and 35 respectively for causing the lower one of said ends to fall by gravity to the lowermost part of the receptacle regardless of the position in which the same is held.

The valve cylinder 31 comprises a body part having a centrally located longitudinally disposed opening 36 surrounded at each end by protruding annular rims 37 and 38. The interior of the body part is cut away at each end, and a pair of caps 39 and 40 to which the flexible discharge pipes are secured are slipped thereover forming annular chambers of somewhat larger diameter than the central passage 36.

Means are provided for closing the ends of the passage 36 and comprise a pair of cup-shaped valve heads 41 and 42 disposed with their open ends facing each other, and connected together by a stem 43 which passes through and is considerably smaller than the passage 36. The flanges or rims of the cup-shaped valves 41 and 42 have sliding fit over the protruding annular rims 37 and 38, and are provided with ports 44 located so as to provide communication between the passage 36 and one or the other of the chambers at the ends thereof. The valve heads are slideable by gravity and, being connected by the stem 43, move as a unit, closing the upper valve and opening the lower one.

Means for providing communication between the passage 36 and the discharge nozzle 20 are provided and comprise a pipe 45 disposed longitudinally of the pump cylinder and preferably diametrically opposite the valve cylinder 31. The lower end of the pipe 45 communicates with the interior of the tubular fitting 23 into which the nozzle 20 is threaded, and the upper end is bent around the pump cylinder and is attached to and communicates with the valve cylinder 31. A ball check valve 46 may be provided for stopping any back flow of fluid.

In the operation of the apparatus, the casing may be filled with fire extinguishing

liquid through the filler opening by removing the plug 4. When the apparatus is not being used, the piston rod is thrust inward to its full limit and turned to the right so that the inclined shoulders 29 wedgingly engage under the inwardly faced flanges 30. When the piston rod is in this position, the valve stem 24 is shifted downward against the action of the spring 26, so that the valve head 25 coacts with the valve seat 22, and effectively prevents any escape of liquid from the apparatus.

When it is desired to use the apparatus, the handle 10 is turned to the left thereby disengaging the shoulders 29 and allowing the spring 26 to raise the valve head 25 from the valve seat 22. The handle is then reciprocated in the usual pumping manner, and when the handle is pulled outward the piston 8 slides downward against the shoulder 15 of the end piece 13, and this causes the air to be drawn inward through the valve 18 into the pump cylinder 5. On the return stroke when the piston rod is thrust inwardly, the piston 8 slides up against the shoulder 14 as shown in Fig. 2, thus allowing the air in the cylinder 5 to pass into the elongated slot 16 on the lower side of the piston 8 and out of said slot on the upper side of said piston, the check valve 18 preventing the escape of air from the cylinder. The piston rod 9, however, is of comparatively large diameter, and consequently displaces a considerable amount of air which has been drawn into the cylinder 5, said air passing out through the discharge valve 19 into the casing 1. When the piston is again drawn outward, the air in the casing 5 on the upper side of the valve 8 is discharged through the valve 19 and new air is drawn in below the piston.

The building up of the air pressure in the casing 1 forces the fire extinguishing liquid therein out through one or the other of the flexible discharge tubes. When the fire extinguisher is held in an inclined position or an upright position, as shown in the drawings, the cup-shaped valves slide, by gravity, so as to close communication through the upper intake pipe and open communication through the lower intake pipe.

The weights 34 and 35 on the free ends of the flexible discharge pipes cause said pipes to assume a lowermost position at all times in the casing, so that one of said ends will dip into the fire extinguishing liquid at all times regardless of the position in which the fire extinguisher is held.

Cross reference is hereby made to my co-pending application Serial No. 104,189, filed June 17, 1916.

Although but one specific embodiment of this invention has been herein shown and described, it is to be understood that the construction may be altered or details omit-

ted without departing from the spirit of this invention as defined by the following claims.

I claim:

1. An apparatus of the class described, comprising an elongated tubular receptacle adapted to contain a liquid, a pump cylinder rigidly mounted in said receptacle, a valve casing rigidly mounted in said receptacle medially of the ends thereof, a pair of flexible discharge pipes each having one end thereof mounted on and communicating with said valve casing, the other end of each of said discharge pipes being freely movable and being weighted for causing them to hang downward in said casing, a discharge nozzle communicating with said valve casing, and a piston slidably mounted in said pump cylinder, said pump cylinder having an air inlet communicating with the atmosphere and an air outlet communicating with the interior of said receptacle, all being adapted to pump air into said receptacle and to discharge the liquid through said discharge pipe, valve casing, and nozzle.
2. An apparatus of the class described,

comprising a tubular receptacle adapted to contain a liquid, a pump cylinder mounted in said receptacle, a valve casing mounted in said receptacle medially of the ends thereof, a pair of flexible discharge pipes each having one end thereof mounted on and communicating with said valve casing, the other end of each of said discharge pipes being freely movable and being weighted for causing them to hang downward in said casing, a discharge nozzle communicating with said valve casing, and a piston slidably mounted in said pump cylinder, said pump cylinder having an air inlet communicating with the atmosphere and an air outlet communicating with the interior of said receptacle, all being adapted to pump air into said receptacle and to discharge the liquid through said discharge pipe, valve casing and nozzle.

Signed at Chicago this 15th day of June, 1916.

WALTER T. CHARLES.
